UNITED STATES PATENT OFFICE.

WILLIAM JOSEPH STILL, OF LONDON, ENGLAND.

INTERNAL-COMBUSTION ENGINE.

1,145,392.

Specification of Letters Patent.

Patented July 6, 1915.

Application filed January 18, 1913. Serial No. 742,878.

To all whom it may concern:

Be it known that I, WILLIAM JOSEPH STILL, of London, England, have invented certain new and useful Improvements in and Connected with Internal-Combustion Engines, of which the following is a specification.

This invention relates to improvements in and connected with internal combustion engines and has particular reference to engines of that type wherein the waste heat of the engine is employed to generate or assist in the generation of steam for use expansively to increase the power of the engine.

It is of primary importance—particularly in this type of engine—to maintain the cylinders at a constant temperature throughout their whole length, and in order to accomplish this and at the same time to advantageously utilize the large amount of heat usually lost to these cylinder walls, I provide as has previously been proposed an evaporating jacket surrounding the cylinders connected by in-flux and efflux pipes to a boiler drum so situated as to enable the water level within the drum to be maintained above the level of the crown of the jacket. The boiler drum will itself be heated by the exhaust from the combustion cylinders acting on suitable heating surfaces and separate firing means may if desirable be provided for starting up and overload purposes. Under these conditions the jacket will be maintained at the evaporating temperature of the boiler, say for example 380° F. instead of at about 180° F., which is a common outlet temperature for ordinary water jackets and this will render it essential that the cylinder walls be kept thin so as to reduce the difference between the temperature of the inner and outer surfaces to a minimum.

My present invention consists primarily of a cylinder construction which renders this possible and this construction consists broadly in producing a thin cylinder strengthened by external pressure resisting means. This provision of a thin cylinder is of great importance in the case of large internal engines—whether of this particular type or not—which normally require to be of considerable thickness. It should be noted that in speaking of a thin cylinder I mean a cylinder which without some extraneous strengthening means such as I propose to adopt would not be regarded in com-

mon practice as sufficiently thick to stand the strains to which it is subjected.

To render the use of a thin cylinder wall possible without unduly weakening the cylinder as a whole, I propose to encircle the thin cylinder with a pressure resisting band separated from the cylinder by longitudinal ribs. These ribs are preferably cast in one with the cylinder and extend over the high pressure zone, their outer faces or edges being turned to receive a wrought steel or other suitable sleeve which is pressed over them. The ribs aforesaid are preferably thickened at their roots to insure ample heat conducting areas. By this means the water flowing to the jacket will have access to parts comparatively close to the inner surfaces of the cylinder walls and yet ample strength will be provided to withstand the combustion pressures.

In the accompanying drawings I have illustrated my invention, Figure 1 being a more or less diagrammatic view illustrating an engine cylinder in its preferable relation to the steam boiler or generator. Fig. 2 is a cross sectional plan view of the engine cylinder on line A—B of Fig. 1. Figs. 3 and 4 are sectional elevations on planes at right angles to each other of modified applications of my invention. Fig. 5 is a plan of the cylinder with the cover removed. Fig. 6 is a sectional elevation of an engine having opposed pistons and the combustion chamber between them with my invention embodied therein and adapted thereto. Fig. 7 shows a modified method of performing my invention after the manner shown in Fig. 6.

Referring to these drawings and particularly to Figs. 1 and 2 the numeral 1 designates the cylinder provided with a piston 2 which is coupled up to the crank shaft (not shown) by means of the usual connecting rod 3. The bottom end of this cylinder is closed by a cylinder cover 4 provided with a stuffing box 5 through which the piston rod 6 passes. The piston 2 is preferably hollow and the cylinder cover conforms to its internal shape as shown. The combustion chamber of the cylinder is located at the top of the piston and is provided with the usual sparking plug at 7 and inlet and exhaust valves. The part of the cylinder below the piston constitutes a steam expansion chamber, the steam being admitted to this steam chamber and exhausted therefrom through the piston slide valve 8 operating in

the steam chest 9. The wall of the cylinder 1 is comparatively thin and is provided with ribs 10 cast integral with it and these ribs are preferably thickened at the roots 11. A 5 wrought steel sleeve 12 encircles the ribs 10 of the cylinder.

In order to provide for the ready inspection and cleaning of the outer surfaces of the cylinders and the inner surfaces of the 10 jacket I may form the outer shell of the jacket in the form of a removable wrought iron cap. This cap is preferably jointed to the cylinder by means of a flanged joint at one end while the other end forms a gland 15 or stuffing box joint with the upper part of the cylinder which carries the necessary valves. These valves are carried preferably in tubular extensions proceeding from the head to permit of good water circulation. 20 The ribs 10 do not extend the full length of the cylinder but extend over the high pressure zone. The sleeve 12 may be lagged in any suitable manner. The cylinder head 13 carrying the sparking plug and valves is 25 provided with water spaces which are in communication with the cylinder jacket spaces between the cylinder wall and the sleeve 12 aforesaid.

The numeral 14 designates a steam boiler 30 which is arranged with the water level above the crown of the cylinder jacket and a pipe 15 leads from this boiler and is connected by the passage 16 with the cylinder jacket formed as aforesaid by the pressure resisting sleeve 12. A second pipe 17 leads from the cap or cover 13 back to the boiler 14 and thus a complete water circulation is provided from the boiler to the cylinder jacket and from the cylinder jacket back to the 35 boiler, the cylinder jacket forming a definite part of the boiler system. A pipe 18 conducts the exhaust from the combustion chamber to the steam boiler which may also be provided with additional firing 40 means for starting and overload purposes as will be readily understood by those conversant with this type of engine. The exhaust gases pass along the fire tubes 19 of the boiler into a smoke box 20 in which a feed water heater 21 is located. A steam pipe 22 leads from the boiler 14 to the steam chest 9. The provision of the ribs 10 on the cylinder body not only provides in conjunction with the sleeve 12 an effective means for 45 strengthening the otherwise weakened cylinder walls, but it also provides ample surfaces over which the water can circulate while the removability of the sleeve 12 provides for the ready inspection and cleaning of the outer surfaces of the cylinders and the inner surfaces of the jacket pressure resisting sleeve. Where the sleeve 12 is removable it is preferably turned taper and forced over the ribs 10 so as to produce tension within it on erection so as to obviate any tendency upon the

part of the cylinder to crack before the strain is transmitted to the sleeve. It is not however essential for the sleeve to be removable and in Figs. 3, 4 and 5 I have shown an example where the sleeve designated by the numeral 23 is shrunk on to the ribbed cylinder 24 and a flange 25 forming part of the cylinder and the bottom of the water jacket. In this case the cylinder head 26 in the form of a hollow drum is removable being provided with grooves 27 which fit on to the tops of walls of the cylinder 24 and sleeve 23 and is secured in position by studs 28 which screw into certain of the ribs 29 cast on the cylinder wall. The hollow drum 26 forming the cylinder head carries the usual sparking and valve arrangements, the ports 30 of the valves passing through this drum. The drum has water circulation ports such as 31 for permitting the circulation of water from the jacket to the drum. The ports 31 are so located that a port occurs over each space between the ribs of the cylinder as shown in Fig. 5. The water from the boiler enters the jacket through the opening 32 and passes into the drum 26 and back to the boiler through the opening 33 in the drum in the manner described in relation to Fig. 1.

In Figs. 6 and 7 I have shown a two cylinder engine constructed upon the same lines as that described in the specification of my prior British Letters Patent No. 25356 of 1910. In this type of engine owing to the necessity for valve chambers 34 surrounding the cylinder wall, the sleeve 35 cannot conveniently be passed over the pressure zone. In order to enable the present invention to be applied to this type of engine, I construct the cylinder in three portions, a central 105 ribbed portion 36 surrounding the pressure zone and two end portions 37, 38. By this means the sleeve 35 is arranged on the portion 36 of the cylinder before the engine is assembled. Rings 39 are used to close the 110 ends of the water jacket which here again forms part of the circulating system of the boiler as before described. The cylinder portion 36 is placed upon and supported by the flange or table 40 cast on the cylinder 115 portion 38 which is shown in this example integral with the engine frame. The upper portion 37 of the cylinder rests upon and is supported by the top ring 39 aforesaid and the two cylinder ends 37 and 38 are drawn together by long bolts (not shown). These bolts pass close to the sleeve 35 and are embedded in the lagging around the sleeve. The portions 37 and 38 of the cylinder as a 120 whole form the steam expansion chambers of the engine and they are provided with sockets 41 and 42 in which steam circulates on its way to the steam chest. During the working of the engine the temperature of the cylinder 36 will be somewhat higher 125 130

than that of the sleeve 35. The cylinder 36 will therefore expand to a greater extent than the sleeve and in so doing probably set up excessive strains within the structure.

5 I propose to relieve the structure of these strains by constructing the rings 39 as shown in Fig. 7. They are rounded on the surface abutting against the top and bottom castings as shown at 43 and are reduced in 10 thickness by providing in each of them a groove 44. The pressure produced by the expansion of the cylinder will cause sufficient distortion of the rings to relieve these strains and prevent injury to the packing or 15 other jointing material.

What I claim and desire to secure by Letters Patent is:

In an internal combustion engine, a cylinder of abnormal thinness and incapable

of withstanding the working pressures incidental to the operation of the engine, longitudinal ribs cast integral with the cylinder, openings in the ribs to permit of the circulation of the cooling medium, and a pressure resisting jacket shrunk on the cylinder in compressive engagement with the ribs aforesaid whereby the working pressures within the cylinder are transmitted to the jacket through the ribs, the jacket being spaced from the cylinder at intervals whereby to provide a space for the circulation of a cooling medium.

In testimony whereof I affix my signature in presence of two witnesses.

WILLIAM JOSEPH STILL.
